UNITED STATES PATENT OFFICE.

FRED A. PHILBRICK, OF SANTA CRUZ, CALIFORNIA.

WELL-DRILLING APPARATUS.

Application filed November 4, 1925. Serial No. 66,802.

This invention relates to improvements in well drilling apparatus, and has particular reference to means for gripping the drilling cable.

5 The principal object of this invention is to provide means for gripping a drilling cable which means will eliminate the customary slippage, between the cable and the hoisting mechanism.

10 Another object is to produce a cable gripping means which may be attached to any ordinary drilling rig now in use without altering the construction of the same.

A further object is to produce a device 15 of this character which is simple in construction and therefore cheap to manufacture.

A still further object is to provide means whereby the gripping will be sufficiently secure to permit "jerking" without slippage.

20 Other objects and advantages will be apparent during the course of the following description.

In the accompanying drawings forming a part of this specification and in which like 25 numerals are employed to designate like parts throughout the same,

Figure I is a side elevation of a cable clamp having my runner clamps mounted therein,

30 Figure II is a top plan view of my runner clamps.

Figure III is a side elevation of Figure II,

Figure IV is a side elevation of one of the halves of my runner clamp, and

35 Figure V is a vertical cross-section showing my runner clamp in engagement with a cable.

In the drilling of oil wells and the like deep wells, a drilling tool weighing a considerable amount is attached to the end of the cable, which cable is lowered into the well. A rig positioned adjacent the well has a rocker beam to which is attached by means of a chain or similar means, a clamp which 45 clamp is in turn adapted to engage the cable extending into the well. The rocker beam when actuated causes the cable to be reciprocated in the well so as to cause the drill to be lifted and lowered.

50 As the well deepens, the rocker beam is stopped and a new grip taken upon the cable the cable being lowered sufficiently to compensate for the increased depth of the well. It is the connection between the cable and the clamp carried by the rocker beam that 55 has given considerable trouble due to the

slippage caused by the weight of the cable and its attached parts.

I have sought to overcome this slippage by providing a new form of runner clamp 60 to be inserted in the main clamp, which runner clamp is provided with a facing of softer metal than that forming the cable, and by referring to the drawings it will be noted that the numerals 5 and 6 designate 65 links of a chain connected to the rocker beam, while the numeral 7 designates the cable extending into the well being drilled. Supported from the links 5 and 6 as by horns 8 and 9, are clamp sections 11 and 12, 70 respectively. These clamp sections are pivoted together so as to be easily clamped around the cable and are provided with outwardly extending ears 13 and 14.

The ear 13 carries guide pins 16 upon 75 which a block 17 is adapted to be moved. This block has passing therethrough a screw 18 to which is attached a handle 19. The end of this screw bears against the ear 13.

At 21 I have shown a yoke pivoted to the 80 block 17, which yoke is adapted to straddle the ears 13 and 14 and has the handle 22 for the purpose of manipulating the same.

The construction thus far described relates to all standard well drilling operations. 85 At the present time, slip clamps are employed within the main clamp the same being merely plain castings of a conformation similar to that illustrated in Figure II. It is these clamps that I improve by providing 90 them with a soft lining 23. The two halves of the slip clamp are designated by the numerals 24 and 26. A head 27 is formed upon each so as to retain the same within the clamp sections 11 and 12. 95

By viewing Figures IV and V, it will be noted that the lining 23 is flowed onto the clamp section as for instance, the clamp section 24, thereby leaving the same in a roughened condition. This rough condition further assists in maintaining a grip between the clamp and the cable. 100

An approved method of flowing a soft metal onto the clamp sections is to employ a brass rod, one end of which is connected to 105 an electric cable and to bring the end of this rod into contact with the clamp section which is also connected to an electric cable with the result that an arc occurs and the brass rod is melted onto the surface of the 110 clamp section.

Referring to Figure V, it will be noted

that the strands of the cable will embed themselves in the soft metal of the clamp sections thereby effectively locking the clamp to the cable in such a manner that longitudinal movement is impossible.

Heretofore it has been necessary to place a long piece of pipe upon the handle 19 of the screw 18 to exert excessive pressure upon the clamp sections in order to grip the cable, but even then when "jerking" was resorted to for loosening the stuck tool, the cable would often slip within the clamp.

With my device the gripping action is so positive that very little pressure has to be exerted upon the handle 18 in order to tighten the clamps sufficient to prevent any slippage.

It is to be understood that the form of my invention herewith shown and described is to

be taken as a preferred example of the same and that various changes in the shape, size and arrangement of parts may be resorted to without departing from the spirit of the invention or the scope of the subjoined claim.

Having thus described my invention, I claim:

In a clamp, a pair of elongated cooperatively associated semi-circular members, having the same cross-sectional area throughout their length, a liner secured in each semi-circular member by flowing the same therein whereby a roughened surface will be provided on the inner surface of said lining, and said liner being of a softer material than the material forming the semi-circular members.

In testimony whereof I affix my signature,

FRED A. PHILBRICK.
